CABLE REEL LAGGING

Harold V. Schmidt, Oak Park, Ill., assignor to
 Western Electric Company, Incorporated, New
 York, N. Y., a corporation of New York

Application February 26, 1937, Serial No. 127,900

2 Claims. (Cl. 206--59)

This invention relates to reels for transporting heavy material, such as lead covered cables, and is particularly directed to providing an improved form of lagging for such reels.

Objects of the invention are to provide for such reels a lagging of simple, inexpensive and durable construction, of a universal type adaptable to reels of various sizes and constructions, and of a form capable of being easily and quickly secured in place on the reel.

In accordance with the above objects, one embodiment of the invention contemplates the provision of an improved form of cable reel lagging, in which a plurality of sheet metal lags of substantially channel-like cross-section are placed side by side across the outer peripheries or rims of the reel heads to form a complete covering or enclosure for the cable storage space of the reel. An important feature of the invention resides in increasing the strength of this form of lagging, and more particularly the resistance thereof to impact stresses, without increasing materially the weight of the lagging. This is accomplished by reinforcing the rim engaging end portions of the lags, preferably by increasing the wall thickness thereof; for example, by inserting and welding within each end portion of the lags a metallic filler, gusset, or liner in the form of a short channel member conforming in cross-section to the shape of the lag. Each of the reinforcing liners may be formed with a depending wall portion adapted to serve as a closure member at the adjacent end of the lag. The lags may be formed with transverse grooves in their outer surfaces for receiving and retaining metal bands for holding the lags in place on the reel.

A more complete understanding of the novel features and advantages of the invention will become apparent in the following detailed description, when read in conjunction with the accompanying drawing, in which

Fig. 1 is a side elevational view, partly in section, of a cable reel provided with an improved form of lagging embodying the invention;

Fig. 2 is an enlarged fragmentary end view, partly in section, of the reel and lagging shown in Fig. 1;

Fig. 3 is a perspective view of an end portion of one of the lags;

Fig. 4 is a perspective view showing one of the reinforcing members prior to its insertion within the end portion of a lag;

Fig. 5 is a fragmentary sectional view of an end portion of one of the lags in position on the rim of one of the reel heads; and

Fig. 6 is a view similar to Fig. 5 showing an alternative form of lag embodying the invention.

Referring now to the drawing, a preferred form of lagging embodying the invention is illustrated; for example, in conjunction with a cable reel comprising a pair of spaced heads 10, 10 interconnected by a drum 11 for holding a cable 12, or other heavy material that may be wound thereon. The cable reel itself may be of any suitable construction, although a welded all-metal construction is preferred. In the construction illustrated, the heads each comprise an inner annular channel member 13, an outer annular rim 14 concentric therewith, channel spokes 15 extending between the inner annular channel member and the rim and welded thereto, and an annular metallic disc or head sheet 16 welded to the spokes on the side facing the drum. The spokes may be notched at their inner ends, as shown in Fig. 1, to receive the ends of the drum and outwardly turned inner flanges 17 of the head sheets, which, together with the drum, may be welded to the annular channel 13. In the construction illustrated, the spokes 15 are also notched at their outer ends to receive outwardly turned outer flanges 21 of the head sheets, which may be welded to the under side of the rims 14.

The improved form of lagging comprises a plurality of lags 25 of uniform size and construction and sufficient in number so that when placed side by side on the rims 14 and lengthwise across the width of the reel, as shown in Figs. 1 and 2, a complete covering or enclosure is provided for the cable storage space of the reel. The lags are preferably of channel-like cross-section and formed from sheet metal. Each lag comprises a substantially flat web portion 26 and integral depending side arms or flanges 27, 27 on opposite sides thereof. As best shown in Fig. 2, the flanges 27 are flared outwardly slightly and at their bottom edges they are formed with outwardly extending open beads to provide rigidity.

The lags are placed on the reel so that the bottom edges of the flanges 27 thereof contact the rims 14, the web portions 26 of the lags being spaced from the rims, as shown in the drawing.

The rim engaging end portions of the lag flanges 27 are preferably narrowed or reduced in depth by notching the bottom end corners of the flanges, as indicated at 29 (Fig. 3). The resistance of the lags to impact stresses is thereby increased. Also, the notched corners permit the remaining unnotched portions of the lag flanges 55

to project inwardly between the reel heads and thereby serve as braces therebetween.

In accordance with an important feature of the present invention, the strength of the lags 25 and their resistance to impact stresses are increased substantially without increasing materially the weight of the lags. This is accomplished by reinforcing the rim engaging end portions of the lags by increasing the wall thickness thereof, preferably by inserting and welding within the end portions a filler or gusset 30 in the form of a short metallic channel member of a cross-section conforming to the cross-section of the notched end portions of the lags. Each reinforcing gusset or channel member 30 comprises a web portion 31 and a pair of depending side arms or flanges 32, 33. The dimensions are such that the reinforcing channel fits fairly snugly within the notched end portions of the lags, where it may be secured, for example, by spot welding, as indicated at 34 (Fig. 3). It will be noted that the bottom edges of the flanges 32 of the reinforcing channels are flush with the bottom edges of the notched end portions of the lag flanges. Thus, the durability and strength of the lags are materially increased and their resistance to impact stresses, such as are encountered in normal service, is substantially increased, particularly at the rim engaging portions of the lags where the greatest strength is required.

Each of the reinforcing channels 30 may be formed with a vertical wall portion 33, preferably formed integral with the web portion 31 and depending therefrom, as illustrated in the drawing. This vertical wall 33 serves as a closure for preventing cinders, stones, etc., from entering the cable storage space of the reel through the otherwise open ends of the lags. In order that the lag flanges may not be restrained from spreading slightly when under pressure so as to distribute the load over a plurality of lags, the vertical wall portion 33 of the reinforcing channel is preferably not secured to the lag flanges along their adjoining edges. Also, in the preferred construction, shown in Figs. 1 to 5, inclusive, the height of the wall portion 33 is slightly less than the flanges 32 of the reinforcing channel so that sufficient clearance is provided between the rims of

the reel heads and the bottom edge of the wall portion 33 to permit a free spreading movement of the lag flanges.

In the alternative construction shown in Fig. 6, the lag projects slightly beyond the outside edge 5 of the rim 14, so that the vertical wall portion 33 of the reinforcing channel 30 can be extended inwardly beyond the peripheral surface of the rim on the outer end surface thereof, as shown.

The improved lags are adapted to be held in 10 place on the reel by metallic bands 36 which are received in transverse retaining notches 35 formed in the outer surfaces of the lags.

It is to be understood that the invention is not limited to the specific embodiments thereof here- 15 illustrated and described except insofar as is defined by the appended claims.

What is claimed is:

1. A cable reel comprising spaced heads, a drum connected therebetween, and a plurality of 20 sheet metal lags of channel cross-section extending between said heads and having the free edges of their flanges in contact with the peripheral surfaces of said heads, each of said lags having a metallic reinforcing member of channel cross- 25 section welded within each end thereof with the web and flange portions of the reinforcing members in contact with the web and flange portions, respectively, of the lags, each of said reinforcing members having a flap portion depending from 30 its web portion for closing the ends of the lags.

2. A lag for a cable reel having spaced heads, comprising a sheet metal channel member adapted to span said heads and attachable thereto with the free edges of the flange portions at one end 35 of said channel member in contact with the peripheral surface of one of said heads, and reinforcing means secured within said end of said channel member, said reinforcing means comprising a sheet metal liner of channel cross section having a web portion contacting and welded to the web portion of the channel member and flange portions contacting and welded to the corresponding flange portions of the channel member, the said liner having a flap portion depending 40 from its web portion for closing the said end of the channel member.

HAROLD V. SCHMIDT.
